UNITED STATES PATENT OFFICE.

ALOYSIUS C. LIPPERT, OF KENOSHA, WISCONSIN, ASSIGNOR, BY DIRECT AND MESNE ASSIGNMENTS, TO THE NORLIPPE COMPANY, OF CHICAGO, ILLINOIS, A CORPORATION OF ILLINOIS.

RADIATOR CAP.

Application filed August 11, 1924. Serial No. 731,291.

My invention relates to radiator caps for automobiles and the like, and has for a primary object the provision of an improved locking device for preventing theft of the cap or the motometer carried thereby by unauthorized removal of the cap from the radiator neck.

In U. S. Letters Patent No. 1,472,878, granted on November 6, 1923, to Aloysius C. Lippert and John A. Sinko, a radiator cap construction involving the use of a relatively light and inexpensive insert, or inner attaching collar, made of brass or other bendable material, is shown and the present invention is particularly adapted to a radiator cap using this form of insert, though it will be evident that, from certain aspects, it is not limited to use with an insert of any particular form or material.

An important object of the invention is the provision of a radiator cap, of inexpensive yet sturdy and efficient construction, which can be provided at a price which will render them practical for small cars and which will be capable of withstanding hard service without breakage or disturbance of proper relationship of the parts.

Numerous other objects and advantages of the invention will be apparent as it is better understood from the following description, which, taken in connection with the accompanying drawings, discloses a preferred embodiment thereof.

Referring to the drawings,

Figure 1 is a front elevation, partially broken away and shown in section, of a radiator cap in which my invention is embodied, the same being shown in position upon the radiator of an automobile;

Fig. 2 is a transverse sectional view, taken substantially upon the section line 2-2 in Fig. 1; and

Fig. 3 is a similar view, taken upon the section line 3-3 in Fig. 1.

As thus illustrated, the radiator cap provided by my invention comprises an outer body 11, which has tapered arms 12 extending from the opposite sides thereof, said arms terminating in round balls 13 and the body of the cap being adapted to be locked to the radiator neck by means of an inserted member 14, a hinged cover 15 being provided to permit filling of the radiator with water.

A motometer 16 is carried by the cover 15, being preferably locked thereto in permanent manner, and it will be evident that inasmuch as the cap itself is permanently locked to the radiator neck, theft of said motometer, either by removing it from the radiator cap or by removing the cap from the car, will be prevented. Said cover 15 is adapted to be fastened down in steamtight relationship to the body of the radiator cap by means of a thumb-screw 17, or in any other preferred manner, a gasket 18 being provided in the upper part of the body to cooperate with said cover in producing a tight fit. Said gasket has a flange 19 extending into a circumferential recess 21 in the upper interior part of the cap body 11, the inner faces of the gasket being beveled and the lower extension 22 thereof being adapted to fit within a ledge 23 formed on the top of the insert 14.

Said insert 14 is provided with a threaded portion 24 at the lower end thereof adapted to cooperate with a threaded portion 25 of the radiator neck to secure said cap in place, it being obvious that, in any event, if the radiator neck is externally threaded, as is sometimes the case, the insert would be internally threaded and the outer body 11 extended downwardly to prevent any substantial portion of the insert being accessible from the exterior.

It is intended that the parts of the cap may be assembled prior to positioning upon the car and that the outer body 11 and insert 14 may be connected together to form a single unit when the cap is being screwed onto the radiator, but that the outer cap body shall be relatively movable with respect to the insert when turned in the opposite direction so that the insert cannot be unscrewed by mere turning of the outer body after the cap has been placed upon the car. For the purpose of causing the parts to turn together when the cap is screwed down, I provide a ratchet device comprising a metal strip 26, folded upon itself and laid in a recess 27 formed in the exterior of the insert 14, said strip 26 being of resilient material and adapted to have an end 28 thereof project outwardly into a recess 29 in the body when said body is turned in direction to screw the cap onto the radiator. The recess 29 is beveled at one side, as indicated

at 31, so that when the body 11 is turned in the opposite direction, the ratchet strip 26 will move past said recess without effect upon the insert 14, so that the latter will remain in position independently of pressure exerted upon the exposed portions of the cap.

For the purpose of preventing separation of the cap body 11 and insert 14, I provide a groove 32 on the upper part of said insert 14, exteriorly thereof, and insert small pieces of wire or rod 33 in openings 34 in the outer body 11, said rods extending into the groove 32 at a tangent with respect to the insert 14. The outer ends of the rods 33 are rounded, as indicated at 35, so that they are flush with the periphery of the body 11 and cannot be removed by means which are ordinarily available after they have been inserted. Also, they are held in place by a drive fit which prevents them from coming out. The inner ends of said rods extend into the material of the body 11, as indicated at 36, beyond the locking portions 37 thereof, and said locking portions are disposed tangentially in the groove 32 throughout a considerable portion of their length so that the parts 11 and 14 are held securely in assembled relationship.

It is thought that the invention and many of its attendant advantages will be understood from the foregoing description, and it will be apparent that various changes may be made in the form, construction and arrangement of the parts, without departing from the spirit and scope of the invention, or sacrificing all of its material advantages, the form hereinbefore described being merely a preferred embodiment thereof.

I claim:

1. A radiator cap, comprising an inner member attachable to the radiator neck of an automobile or the like, an outer member enclosing said inner member, a cover hinged to said outer member, a motometer permanently secured to said cover, and means extending in through said outer member and arranged tangentially to said inner member for securing said members together against theft.

2. A radiator cap, comprising an inner member attachable to the radiator neck of

an automobile or the like, an outer member enclosing said inner member, a cover hinged to said outer member and adapted to carry an auxiliary device, and means disposed in said outer member and extending tangentially between said members for locking the same together in non-separable relationship.

3. A radiator cap, comprising an inner member attachable to the radiator neck of an automobile or the like, an outer member enclosing said inner member, a cover hinged to said outer member and adapted to carry an auxiliary device, and means disposed in said outer member and extending tangentially between said members for locking the same together in non-separable, though relatively rotatable, relationship.

4. A radiator cap, comprising an inner member attachable to the radiator neck of an automobile or the like, an outer member enclosing said inner member, a cover hinged to said outer member and adapted to carry an auxiliary device, and means disposed tangentially between said members for locking the same together in non-separable relationship, said means being insertable through said outer member, but not withdrawable from the exterior thereof.

5. A radiator cap, comprising an inner member attachable to the radiator neck of an automobile or the like, an outer member enclosing said inner member, a cover hinged to said outer member and adapted to carry an auxiliary device, and means disposed tangentially between said members for locking the same together in non-separable relationship, said means comprising an elongated member carried in the outer member and engageable in a groove in the inner member, thus providing a substantial extent of contact and holding the members securely in assembled relationship.

6. A radiator cap comprising an outer sleeve, a bendable tubular member disposed within said sleeve and having means for attachment to the threaded filling opening of a radiator neck, said member having a horizontal groove rolled therein, and a horizontally disposed locking member carried by the sleeve and engaging in said groove to lock the cap against theft.

ALOYSIUS C. LIPPERT.
